Attorney

UNITED STATES PATENT OFFICE.

WELLINGTON R. REYNOLDS, OF MADISON, SOUTH DAKOTA.

GLARESHIELD FOR HEADLIGHTS OF VEHICLES.

Application filed November 23, 1925. Serial No. 70,856.

This invention relates to improvements in glare shields for headlights of vehicles.

An important object of the invention is to provide novel and improved means to prevent the glare of a headlight blinding the driver of an approaching vehicle.

Another object of the invention is to provide means whereby some of the rays of a headlight will be projected in a straight line from the reflector instead of to the side as is usual with the headlights now in use.

Another object of the invention is to provide means whereby the glare shield may be adjusted in relation to the source of light to vary the amount of rays to be cut off from one side of the headlight.

A further object of the invention is to provide a glare shield which may be easily secured in position in a headlight without requiring the services of a skilled mechanic.

A still further object of the invention is to provide a glare shield of the above character which will be durable and efficient in use, one that will be simple and easy to manufacture and one which can be placed on the market at a reasonable cost.

With these and other objects in view, the invention consists in the novel construction, arrangement and formation of parts which will be hereinafter more fully described, claimed and illustrated in the accompanying drawings, in which,

Figure 1 is a front elevation of the usual headlight of an approaching vehicle with the lens partly broken away to disclose the glare shield and its relation with respect to the source of light.

Figure 2 is a sectional view taken on line 2-2 of Figure 1 and,

Figure 3 is a perspective view of the glare shield.

Referring to the drawings in detail, wherein similar reference characters designate corresponding parts throughout the several views, the numeral 5 indicates generally the usual type of headlight having the usual parabola reflector 6, a light bulb 7 and lens 8.

The glare shield 9 is preferably composed of an opaque material, but may be formed of any other material to meet the demands incidental to manufacture.

The shield consists of an elongated plate or blade 10 having one end 11 thereof bent forwardly upon itself along a transverse line 12 to form an acute angle with respect to the blade and being slightly curved to conform to the inner surface of the reflector. The end 11 is also bent along its longitudinal axis forming a convex surface adapted to contact with the concave inner surface of the reflector.

The end 11 of the shield has an elongated slot or opening 13 therein adapted to register with an aperture 14 in the reflector.

Any suitable fastening means such as a bolt and nut 15, is used to secure the shield within the reflector and by this arrangement of the parts the shield is mounted within the reflector of pivotal or sliding adjusting movement with respect to the source of light.

In operation the glare shield is preferably mounted within the reflector upon the left hand side of the light bulb 7 of an approaching vehicle to prevent light rays from being projected from that side of the headlight upon which other vehicles usually pass. To regulate the projected rays it is merely necessary to loosen the fastening means and pivot or slide the shield toward or away from the light bulb. In this manner, the horizontal as well as some of the vertical rays may be deflected.

What is claimed is:

In combination with a headlight reflector, a glare shield, a blade composed of a narrow elongated portion adapted to deflect the rays from a source of light, said blade portion being disposed to lie in a vertical plane and being arranged between the outer side of the lamp and the adjacent marginal portion of the reflector and having its top and bottom edges spaced from the upper and lower marginal portions of the reflector, one end of said blade portion being bent outwardly at an angle to provide an attaching member, and means to adjustably secure the attaching member to the reflector to permit the same to be moved angularly and toward or away from the source of light.

In testimony whereof I affix my signature.

WELLINGTON R. REYNOLDS.
